E. P. THIERINGER.
URINAL FOR FEMALES.
APPLICATION FILED APR. 5, 1916.

1,296,713.

Patented Mar. 11, 1919.

UNITED STATES PATENT OFFICE.

EMMA PAULINE THIERINGER, OF NEW YORK, N. Y.

URINAL FOR FEMALES.

1,296,713.

Specification of Letters Patent. Patented Mar. 11, 1919.

Application filed April 5, 1916. Serial No. 89,192.

To all whom it may concern:

Be it known that I, EMMA PAULINE THIERINGER, a subject of the Emperor of Germany, and a resident of New York, New York, have invented certain new and useful Improvements in Urinals for Females, of which the following is a specification.

The object of this invention is to provide a urinal which may be used with greater comfort than those heretofore constructed, which is more convenient to the requirements of an invalid and which will enable its use without risk of accident or soiling, as hereinafter described.

15 In the accompanying drawings, Figure 1 represents a perspective view of my improved construction; Fig. 2 shows a sectional view taken on line 2—2 of Fig. 4; Fig. 3 shows a sectional view taken on line 3—3 of Fig. 4; Fig. 4 shows a plan view and Fig. 5 shows a similar view of a modified form of my device.

In my construction as illustrated in Figs. 1—4, 1 represents a bottom plate tapering both forwardly and rearwardly from a line approximately central thereof; 2 represents a substantially vertical side wall projecting upwardly from said bottom plate 1; 3 represents a hood superimposed upon the forward portion of the vertical side wall 2, and 4 represents a horizontal flange extending from the side wall 2 inwardly and above a portion of the rearward surface of the bottom plate 1 so as to form a contracted slot 5 which is placed into proper register with the patient's anatomy to receive the urine.

In my improved construction the rearward part of the bed pan is capable of being brought into proper position with regard to the patient and the inturned flange serves the double function of providing a seat and also supporting the buttocks of the patient, and preventing any part of the patient's anatomy from being immersed or coming into contact with the contents of the urinal.

The conformation moreover of my construction, by reason of the forward tapering of the bottom plate 1 and its vertical side wall, permits of a more comfortable adjustment of the device to the patient in so far as its tapered construction permits the legs of the patient to be more comfortably accommodated. For the purpose of permitting the contents to be emptied from the urinal

50 nal the flanged portion 4 terminates short of the hood 3, thus leaving spaces or outlets as at 4^a so that by tilting the urinal toward one side the liquid may be guided out.

In Fig. 5 I have shown a modified construction of my device wherein the hood 3 is dispensed with and in lieu thereof a flange, similar to the flange 4, is substituted to prevent accidental egress of the contents.

In the construction shown in Figs. 1—4, 65 the conformation of the hood is such that if the urine be ejected with considerable force it will be impossible for it to escape, the hood 3 being brought close to the body 70 of the patient. The slotted and flanged portion simultaneously rests beneath and supports the patient, so that the patient may occupy the urinal for a length of time without either discomfort or likelihood of immersing a part of the anatomy. The hood 3 has, 75 on each side, between its base or lower portion and its apex, a concave outer surface to better accommodate the patient's thighs.

While I have shown my invention in connection with two of its specific embodiments, 80 I desire it to be understood that I do not limit myself to such specific embodiments as obviously the details of configuration shown may be varied without departing 85 from the spirit of my invention.

What I claim is:

1. A urinal for females, comprising a flat plate tapering both forwardly and rearwardly, a continuous upright wall along the perimeter of said plate, a member projecting 90 inwardly from the upper edge of said wall at the forward portion thereof, and a flange 95 projecting inwardly from the upper portion of said wall at the rear portion thereof and of substantially uniform width, less than half the width of the tapering forward portion of the bottom plate, thus leaving a longitudinal slot between the inner edge portions of said flange, the forward 100 ends of said flange being spaced from the rear edge of said member, and located on the rearwardly-tapering portion of the urinal, rearwardly of the widest part of the bottom plate, to provide two lateral outlets oblique with reference to the longitudinal axis 105 of the urinal.

2. A urinal for females, said urinal comprising a flat bottom plate tapering from approximately midway of its length toward the front and toward the rear, a side wall 110

rising from said plate, a substantially horizontal flange projecting inwardly from said side wall and over a portion of the surface of the bottom plate, said flange having a 5 cut-away portion forming an outlet for the contents of the urinal, a hood for the front portion of the urinal, said hood rising up-

wardly from the side walls and having at each side a concaved outer surface intermediate its base and its apex.

10

In witness whereof I have hereunto set my hand this 25th day of March, 1916.

EMMA PAULINE THIERINGER.
